UNITED STATES PATENT OFFICE.

ROBERT G. LETOURNEAU, OF STOCKTON, CALIFORNIA.

TELESCOPING SCRAPER.

Application filed December 28, 1925. Serial No. 77,941.

This invention relates to improvements in heavy duty and large capacity scrapers, and particularly represents an improvement over my Patent No. 1,530,779 dated March 24th, 1925.

The principal objects of the present invention are to provide a scraper of this type having an improved and more balanced supporting and drawbar connecting means; a more efficient structure for expanding and telescoping the scoops, and for causing the dirt to be expelled with such telescoping movement; and a more positively acting catch and releasing structure for insuring that the scoops when being drawn out will move in predetermined successive order.

With my improved features great strength and facility of operation of the scraper are obtained without any increase in the complexity of the structure, and without any increase in weight of the parts.

Other objects and advantages of the present construction will become evident on a perusal of the following specification.

These objects I accomplish by means of such structure and relative arrangement of parts as will fully appear by a perusal of the following specification and claims.

In the drawings similar characters of reference indicate corresponding parts in the several views:

Fig. 1 is a side elevation of the scraper with the scoops extended and in a load-carrying position.

Fig. 2 is a similar view with the scoops telescoped and in scraping position.

Fig. 3 is an enlarged longitudinal section of the scoops and endgate in telescoped positions.

Fig. 4 is a plan view of the scoop extending and latch structure taken on the line 4-4 of Fig. 3 looking down.

Fig. 5 is a fragmentary enlarged transverse section of a scoop showing its frame bearing roller, taken on the line 5-5 of Fig. 1.

Referring now more particularly to the characters of reference on the drawings, the numeral 1 denotes the longitudinal side frames of the scraper, preferably of box section and formed of two angles welded together, as indicated in Fig. 5. It may here be remarked that all the main beams of the present structure are of similar formation, since this shape of beam provides the greatest strength and resistance to torsional and

other strains, combined with a minimum weight.

These frames are pivoted intermediate their ends onto the frames 2 of endless track trucks 3 of suitable character, the construction of these trucks forming no part of my invention.

Heavy drawbars 4, converging together at their forward ends to form a clevis 5 for attachment to the draw-head of a tractor are pivoted onto the frames 1 adjacent the connection of said frames with the trucks, and extend thence upwardly so that intermediate their ends said drawbars are a considerable distance above the frames 1.

Rigidly welded to the forward ends of the frames 1, which are ahead of the trucks 3, is the forward scoop comprising side members 6 depending between the frames and a bottom plate 7. The forward end of this bottom plate terminates rearwardly of the forward ends of the sides and carries a transverse cutting blade 8 along such forward edge. Reinforcing members 9 extend upwardly from the sides of the scoop adjacent the front end of the bottom plate and are connected at their upper ends, a certain distance above the sides, by a transverse beam 10. Side teeth 11 are fixed onto the sides 6 and point downwardly at an angle ahead of the blade 8 so that when the scoop is lowered to the ground, said teeth will engage the ground about at the same level as the blade 8, but to the sides of and somewhat ahead of the same. These teeth therefore cut or loosen the dirt to the sides of the blade and prevent the ends of the latter, and the adjacent edges of the sides of the scoop, from being worn round as is usually the case.

On each side of the scoop a brace 12 extends upwardly from the corresponding tooth 11 along the side of the scoop to a connection with a vertical beam 13 which projects upwardly from the adjacent frame 1 at or near the point of pivotal connection of said frame 1 with the truck frame. Another brace 14 extends from the top of said beam 13 to the rear end of the frame 1. Said frame is therefore trussed against vertical deflection. Also it will be seen that said frame and the front scoop form a rigid unit, turnable on the pivotal connections of said frames with the trucks.

The frames and scoop are raised and lowered relative to the drawbar 4 by means of vertical racks 15 connected to the side plates

6, each rack being engaged by a pinion 16. The pinions are driven by an electric motor 17, there being suitable reduction gearing between the motor and pinions enclosed in the housing 18. The housing, motor, and pinions are mounted as a rigid unit on the drawbar structure in any suitable manner. Mounted for longitudinal movement of the frames 1 and for telescoping movement with each other and with the front scoop, are a plurality of scoops 19, each one of course slightly narrower than the others, and with their bottom plates 19^a successively higher than the one ahead. The scoops 19 are also successively longer than each other from front to rear, so that when the forward edges of their bottom plates are alined with each other and with that of the plate 7, the rear ends of said scoops 19 will project beyond each other an equal distance.

To prevent telescoping movement of the scoops beyond such position, the outwardly projecting portions of the bottom plates of the scoops are provided with transverse angle members 20 projecting below each bottom plate between the frames 1, said angle members abutting against each other when the scoops are fully telescoped.

Each scoop 19 at its rear end has vertical beams 21 on the outside of the same, which beams extend between the scoop and the frames 1 and prevent lateral movement of the scoop relative to the frames.

Mounted in connection with each beam 21 is a roller 22 which rides on the corresponding frame 1, the roller being enclosed in a housing 23 which provides suitable bearings for the pin 24 of the roller. The forward end of the bottom plate of each scoop rides on the bottom plate of the adjacent scoop ahead, so as to scrape dirt therefrom, while being free to move upwardly if undue resistance to its contact with the scoop plate below is encountered.

Movable along and between the rearmost scoop 19 is a vertical endgate 25 rigidly mounted on a horizontal frame 26. This gate rests on the bottom plate 19^a of said rearmost scoop, but the frame 26, extending rearwardly from said endgate, is supported from the frames 1 by a roller 27 on each side of the same engaging the corresponding frame 1 and mounted in a manner similar to the rollers 22.

Mounted on the frame 26 is a reversible electric motor 28, which, through suitable reduction gearing enclosed in a housing 29, drives a transverse shaft 30, on the ends of which outside the lateral plane of the scoops are pinions 31. These pinions engage horizontal racks 32 extending lengthwise of the frames 1 and rigidly supported therefrom in parallel and vertically spaced relation thereto.

It will therefore be seen that when the

scoops and endgate are fully extended, and the scoops are loaded, if the motor is then run in one direction, the scoop adjacent the forward section will first be telescoped on the latter, followed in succession by the other scoops to the rear, and finally by the endgate moving along the rearmost scoop.

The forward movement of each scoop is limited as before stated by the angle members 20 under the scoops for successively engaging each other. The telescoping of the scoops takes place from front to rear rather than vice versa, because when all the scoops are loaded the weight of the dirt in the forward scoop of course offers less resistance to the telescoping of the adjacent scoop than the weight of the dirt piled up in front of the other scoops and endgate.

To enable the motor to pull out the endgate and the scoops one by one after they have been telescoped, I provide the following structure:

Mounted in the different members 20 between the bottom flanges of the same and the bottoms of the corresponding scoops are arms 33. These arms are pivoted at one end on fixed vertical pins 34, which are located on the longitudinal center line of the scoops. These arms when the scoops are telescoped, extend transversely of said scoops or are then folded in the members 20.

Pivoted at one end on the different arms intermediate their ends and extending thence to the pins 34 are links 35, the rearmost of these links being pivoted onto a draw head 36 depending from the rear end of the endgate frame 26.

It will therefore be seen that when the endgate moves rearwardly the corresponding arm and link 33 and 35, respectively, will be extended. When the endgate is moved to its rearmost position relative to the rearmost scoop, which position is determined by the overall length of said arm and link, the pull is taken by the pin 34 of the rear scoop, the corresponding arm and link are then extended and the endgate and said rear scoop then move rearwardly as a unit and so on.

The vertical portions of the members 20 are of course slotted longitudinally so as to enable the links and arms to pass from one to the other and to be extended with the extending of the scoops. The total length of the arm and link pairs between adjacent pins 34 increases from front to rear, corresponding to the greater length of the respective scoops.

To prevent each link and arm from being extended into straight alinement with each other, such as would cause a dead center action between said arm and link to be obtained, a block 38 is mounted at the free end of each arm 33 which engages the corre-

sponding link 35 before the latter forms a straight line with said arm.

- To prevent any scoop from being extended out of turn I provide a stop means associated with the arm and link structure. This stop means comprises a pair of vertically alined arms 39 individually pivoted onto and under the bottom plate 7 of the forward scoop, and extending rearwardly 10 thereof on the opposite side of the center line of the scoops from said arms and links. Mounted in the members 20 and located between the pins 34 and arms 39 are vertical stop blocks 40. These blocks are triangular 15 in cross section in a horizontal plane with their apices at their forward ends and with their rear faces extending transversely of the scraper.

The free rear end of one arm 39 has a 20 roller 41 disposed rearwardly of the rear-most block 40 when the scoops are telescoped. This roller is mounted on a vertical axis which is normally located in a transverse plane in the path of movement of said 25 block, the roller being vertically alined with the block. This arm and roller controls the rearward movement of the two rear scoops. A roller 42 is mounted on the other arm 39 and is similarly positioned rearwardly 30 of the rear one of the forward pair of blocks 40, and controls the rearward movement of the front pair of scoops.

Springs 43 connected to the arms 39 tend 35 to prevent their movement from the above described positions. It will therefore be seen that if the rear scoops should tend to be extended ahead of the endgate for instance the block 40 of the rearmost scoop would abut against the roller 41, which 40 would prevent the rear scoop from moving rearwardly, since the catch arm 39 is connected to the immovable front scoop.

I release this roller so that it may pass 45 over the different stop blocks in succession by means of projections on the arms 33, in the form of rollers 44, these rollers being arranged to each engage and move the rollers 41 and 42 laterally away from the different blocks, when each arm and link unit 50 becomes outstretched.

The first and third blocks 40 from the front are a short distance from the corresponding rollers 42 and 41 so that the corresponding scoops can move that distance out 55 of order before being stopped. This could be overcome by providing a stop arm and roller for each stop block, but the advantages would not be sufficient to warrant mounting these additional parts, since the distance the scoops can thus move before being restrained is but a few inches.

Current for the motors is provided from any suitable source, such as from the tractor pulling the scraper, as contemplated in the structure shown in the patent herein-

before referred to. The motor 28 has considerable travel but current can be supplied thereto by flexible cables, trolleys, or otherwise, such as is done in various arts.

It will be noted that the strain of pulling 70 is taken directly by the main frames 1 intermediate their ends and the level of the drawbars 4 is maintained substantially constant at all times irrespective of the tilt of the frame, and the tilting of the latter does 75 not affect the position of the trucks 3, nor interfere in any way with their working movement, to conform to inequalities in the ground surface.

From the foregoing description it will 80 be readily seen that I have produced such a device as substantially fulfills the objects of the invention as set forth herein.

While this specification sets forth in detail the present and preferred construction 85 of the device, still in practice such deviations from such detail may be resorted to as do not form a departure from the spirit of the invention, as defined by the appended claims.

Having thus described my invention what 90 I claim as new and useful and desire to secure by Letters Patent is:

1. A scraper including a frame structure, a forward scoop fixed thereon and open at both ends, another scoop disposed rearwardly of said fixed scoop and movable lengthwise in the forward scoop, and an end-gate structure movable along the rear scoop lengthwise thereof.

2. A scraper including side frames, a dirt carrying element fixed thereon, ground bearing trucks on which the frames are pivoted intermediate their ends, and a drawbar structure independent of but connected to the frames adjacent their connection with the trucks and extending ahead of the frames.

3. A scraper including a frame structure, a scoop fixed thereon and open at both ends and an end gate structure normally disposed to the rear of said scoop and movable lengthwise therewith in a constantly maintained position relative to a vertical plane toward the forward end of the scoop.

4. A scraper including side frames, a dirt carrying element fixed thereon, ground bearing trucks on which the frames are pivoted intermediate their ends, a drawbar structure pivoted onto the frames intermediate their ends and extending ahead of said frames, the dirt carrying element being at the front end of the frames, and the drawbar being above said frames, a driven pinion on the drawbar, and a rack engaging the pinion and extending downwardly to a pivotal connection with said dirt carrying element.

5. A scraper including side frames, a forward scoop fixed thereon, and open at both ends, other scoops disposed rearwardly of

5 said fixed scoop and movable along the frames for telescoping movement relative to each other and to the fixed scoop, and an endgate structure movable along the frames disposed within the rearmost scoop for movement lengthwise therein.

10 6. A scraper including side frames, a forward scoop fixed thereon, and open at both ends, other scoops disposed rearwardly of said fixed scoop and movable along the frames for telescoping movement relative to each other and to the fixed scoop, an endgate structure movable along the frames disposed within the rearmost scoop for movement lengthwise therein, and means for moving said endgate structure mounted thereon.

15 7. A scraper including side frames, a forward scoop fixed thereon, and open at both ends, other scoops disposed rearwardly of said fixed scoop and movable along the frames for telescoping movement relative to each other and to the fixed scoop, an endgate structure movable along the frames disposed within the rearmost scoop for movement lengthwise therein, and means for moving said endgate structure mounted thereon.

20 8. A scraper including side frames, a forward scoop fixed thereon, and open at both ends, other scoops disposed rearwardly of said fixed scoop and movable along the frames for telescoping movement relative to each other and to the fixed scoop, an endgate structure movable along the frames disposed within the rearmost scoop for movement lengthwise therein, means for thus moving said endgate structure, means whereby with such movement in one direction the scoops will be successively telescoped into each other, and means whereby with the movement of the endgate in the opposite direction the scoops will be successively drawn out from each other.

25 9. A scraper including side frames, a forward scoop fixed thereon, and open at both ends, other scoops disposed rearwardly of said fixed scoop and movable along the frames for telescoping movement relative to each other and to the fixed scoop, an endgate structure movable along the frames disposed within the rearmost scoop for movement lengthwise therein, means for thus moving said endgate structure, such movement caus-

30 ing the scoops to be successively telescoped into each other, and foldable arm and link units between the various scoops and endgates and arranged to be extended when the endgate moves in the opposite direction.

35 10. A structure as in claim 9, in which means is provided to cooperate with said units to cause the extending movement thereof to take place in predetermined successive order.

40 11. A structure as in claim 9, in which catch means are provided for holding the scoops against extending movement when telescoped and release means are provided in connection with said arm and link units for engaging and releasing said catch means with the extending of said units in predetermined successive order.

45 12. A scraper including side frames, a forward scoop fixed thereon, and open at both ends, other scoops disposed rearwardly of said fixed scoop and movable along the frames for telescoping movement relative to each other and to the fixed scoop, an endgate structure movable along the frames disposed within the rearmost scoop for movement lengthwise therein, means for thus moving said endgate structure, such movement causing the scoops to be successively

50 telescoped into each other, foldable arm and link units between the various scoops and endgates and arranged to be extended when the endgate moves in the opposite direction, the bottoms of the movable scoops extending beyond each other rearwardly somewhat when the scoops are telescoped, stop-blocks on such extending bottom portions, arms mounted on the fixed scoop and projecting rearwardly therefrom, catch members on said arms disposed rearwardly of and in the path of corresponding stop blocks, and release members mounted on the different arm and link units and positioned to successively engage and release the corresponding catch members when said arm and link units are extended in successive order.

55 13. A scraper including a frame structure, a forward scoop fixed thereon and open at both ends, another scoop disposed rearwardly of said fixed scoop and movable lengthwise in the forward scoop, an end-gate structure movable along the rear scoop lengthwise thereof, and means for moving said end-gate.

60 In testimony whereof I affix my signature.
ROBERT G. LETOURNEAU.
